UNITED STATES PATENT OFFICE.

FRANK HINMAN PIERPONT, OF HORLEY, ENGLAND, ASSIGNOR TO LANSTON MONOTYPE MACHINE COMPANY, OF PHILADELPHIA, PENNSYLVANIA, A CORPORATION OF VIRGINIA.

PUMP FOR TYPE-CASTING MACHINES.

1,149,285.

Specification of Letters Patent. Patented Aug. 10, 1915.

Application filed June 12, 1912. Serial No. 703,264.

To all whom it may concern:

Be it known that I, FRANK HINMAN PIERPONT, a citizen of the United States, temporarily residing at Horley, in the county of 55 Surrey, England, have invented a certain new and useful Improvement in or Relating to Pumps for Type-Casting Machines; and I do hereby declare the following to be a full, clear, and exact description of the same, 60 10 reference being had to the accompanying drawings, forming a part of this specification, and to the figures and letters of reference marked thereon.

This invention relates to pumps for type 65 casting machines, such as are described in the specification of British Letters Patent Nos. 8633/99 and 8980/01 (U. S. Patents 625,998 of May 30, 1899 and 674,374 of May 21, 1901). These pumps are operated at a 70 comparatively high rate of speed to deliver metal to a mold, the capacity of which is varied from time to time for the different type bodies cast and great difficulty exists in preventing the pump from acting irregularly or 75 improperly due either to the fouling of the nozzle or, where there is a drawback of the metal to prevent fouling, to the solidifying of some of the metal in the nozzle due to chilling. If there is too great a drawback 80 of metal from the nozzle further difficulty arises in getting rid of the air in the nozzle which otherwise enters the mold and prevents the production of solid types. Various attempts have been made, with more or 85 less satisfactory results, to overcome these drawbacks, for example, in the specification of British Letters Patent No. 4261/02 (U. S. Patent 720,714, dated Feb. 17, 1903) a valve is placed between the pump piston and the 90 channel leading to the nozzle to prevent too great a drawback of fluid from the nozzle and avoid chilling and the collection of a large body of air, and in order to allow a small drawback and prevent fouling of the 95 nozzle, a by-pass is formed through or around the valve to connect the inlet and outlet channels or passages. This valve is separated from the nozzle by a considerable length of channel in which there is always a 100 large body of metal, and has not got a complete control of the metal in the nozzle.

According to the present invention, there

is placed in the delivery nozzle near to the outlet or tip thereof or between the nozzle and the channel leading from the cylinder, a 55 ball or other non-return valve which is free to be raised from its seat by the metal on each ejection stroke and floats back to its seat on the return stroke of the piston so as to trap some metal in the nozzle itself or 60 prevent a large drawback of metal, allowing only a sufficient drawback to avoid fouling, and to insure that this valve operates properly, there is provided a kicker, actuated at 65 each delivery stroke of the pump, to unseat 70 or insure the unseating of the valve should it stick. Further, in order to prevent or minimize the likelihood of a second shot or double delivery, the nozzle is formed with an obstructed or tortuous passage.

The invention will be described as applied to the pump forming the subject matter of British Letters Patent No. 8980/01 (U. S. Patent 674,374) to the specification of which reference may be had for a detailed description of the construction of and of the operating mechanism of the pump.

Referring to the accompanying drawings: Figure 1 is a sectional elevation of the pump body. Fig. 1^a is a sectional elevation of the 80 nozzle on a larger scale than that of Fig. 1. Fig. 2 is a plan of Fig. 1. Fig. 3 is a section on the line 3—3, of Fig. 2. Fig. 4 is a sectional elevation showing the pump operating mechanism.

A is the non-return valve in the nozzle. B is the lever or kicker for displacing the valve, and C is a plug in the nozzle.

It is not deemed necessary to give a detailed description of the parts of the pump 90 with which the present invention is not directly concerned as these are fully set forth in the specification already referred to, a brief description of the parts sufficient for a clear understanding of the present invention, however, will be given.

The pump cylinder D is set in and is movable relatively to the melting pot E under the action of the levers F F' and a spring F² by which the pump is lifted to engage the 100 nozzle D' thereof with the mold.

G is the pump piston which is reciprocated by levers H H' connected together by a link I, one end of the lever H' being in

engagement with the pump body and the corresponding end of the lever H with the pump plunger or piston. A driving shaft H² is connected by an arm H³ to a rod H⁴ 5 pivotally connected to the free end of the lever H and between the arm H³ and a collar on the rod H⁴ is a spring H⁵.

H⁶ is a vertical shaft carrying a head H⁷ extending beneath the arm H³ and connected to the free end of the lever H¹.

The spring H⁵ normally tends to elevate rod H⁴ and a spring H⁸ tends to hold the parts H³ and H⁷ in contact while the shaft raises the pump to the mold, after which 15 further movement of the shaft acting through spring H⁸ transmits motion to lever H to give stroke to the piston.

The metal in which the pump cylinder D is immersed enters the cylinder when the 20 piston G is at the upper end of its stroke, through the inlet opening d in the cylinder and a cavity g in the piston. The cavity g communicates with an annular cavity g' on the outer periphery of the piston, by a convenient number of passages g² which register with the inlet opening d when the piston is at the upper end of its travel.

K is a valve by which the flow of metal through the inlet opening is controlled. The 30 pump cylinder communicates below the piston with the nozzle D' by a channel D².

According to this invention, a non-return valve A, preferably of ball type, is placed in a small chamber a situated in the nozzle 35 and seats inwardly on a seating a' formed in the chamber. The channel D² leads from the pump cylinder on the delivery side of the piston, to the nozzle. The pump is raised as hitherto to bring the nozzle into 40 contact with a seat on the mold by the mechanism referred to and after the nozzle is seated the pump piston is actuated. As the piston descends it forces the metal in the cylinder along the channel D² and through 45 the nozzle D'. After the metal is injected into the mold, the piston performs its return stroke and the valve A floats down onto its seat as the metal recedes, allowing a sufficient drawback of metal to avoid fouling 50 when the nozzle is lowered from the mold seat, but preventing an objectionable body of air entering the nozzle and channel.

In order to insure that the valve A will be dislodged or unseated at each delivery 55 stroke, a kicker B is provided to act on the valve on or during each delivery stroke of the piston. Preferably this kicker is operated positively by the piston and is in the form of a lever B located in the channel D² 60 and pivoted at d' to the walls thereof. One end of the lever is connected to a rod B' which passes up the bore of the nozzle and terminates a little distance below the valve. The thickness of the rod is such as not to 65 obstruct the flow of the metal through the

nozzle. The other end of the lever B projects below the pump piston in the path of a boss G² thereon and before the piston reaches the lower end of its stroke it acts upon this end of the lever B forcing its other end up against the valve to unseat it should it not have acted.

The plug C in the nozzle prevents the valve A from closing the outlet passage in the nozzle, and the passages C' formed between the walls of the plug and the inner walls of the bore in the nozzle are tortuous passages which break up the flow and tend to prevent a double discharge.

L is a cylindrical liner placed between the piston and the pump cylinder walls to provide for an easy repair when the parts wear out or wear so as to allow leakage. As metal can only flow into the pump cylinder when the piston is at the upper end of its stroke, the piston acts as a valve to prevent leakage through the inlet.

Having thus described my invention, what I claim is:—

1. In a pump for a type casting machine, the combination with a non-return valve disposed in the delivery nozzle between the nozzle and the channel leading to the pump cylinder, of a plug which acts as a stop for the valve there being a passage for the metal to pass the plug, substantially as described.

2. In a molten metal injecting mechanism for type casting machines, the combination with a pump, a discharge passage and a nozzle, of an inwardly seating non-return valve located within the nozzle and operating to retain the molten metal within the discharge passage adjacent said nozzle and to permit of a limited drawback of the metal in the exit opening.

3. In a molten metal injecting mechanism for type casting machines, the combination with a pump and a discharge passage communicating therewith and terminating in a nozzle, of a floating inwardly seating non-return valve located within the nozzle and controlling the opening of the discharge passage, and a kicker operated during the operative part of each discharge stroke of the pump piston, to unseat the non-return valve.

4. In a molten metal injecting mechanism for type casting machines provided with a pump and a discharge passage terminating in a nozzle having an internal chamber, and in combination therewith a non-return valve, located within the chamber in the nozzle and controlling the opening from the discharge passage therein, and a plug partially closing the discharge end of said chamber and acting as a stop for said non-return valve.

5. In a molten metal injecting mechanism for type casting machines equipped with a

pump, a discharge passage therefrom, and a nozzle applied to the discharge end of said passage, and in combination therewith a non-return valve controlling the discharge end of said passage, and a kicker engaged by the piston at the beginning of the operative discharging stroke thereof and acting upon the non-return valve to unseat the latter.

FRANK HINMAN PIERPONT.
